UNITED STATES PATENT OFFICE.

WILLIAM C. MEYER, DECEASED, LATE OF BEVERLY, MASSACHUSETTS, BY ANNE WEBSTER MEYER, ADMINISTRATRIX, OF BEVERLY, MASSACHUSETTS, ASSIGNEE TO UNITED SHOE MACHINERY CORPORATION, OF PATERSON, NEW JERSEY, A CORPORATION OF NEW JERSEY.

SOLE-FITTING MACHINE.

Application filed September 26, 1924. Serial No. 740,100.

This invention relates to improvements in channeling machines. As herein illustrated, the invention is embodied in a power-operated machine of the type in which a sole is fed continuously past the cutting means by cooperating upper and lower feed wheels which progressively engage opposite sides of the sole margin, such machines being commonly employed for channeling and 10 grooving outsoles for McKay sewed shoes.

In machines of the general type above referred to the lower feed wheel supports the work and is immovable vertically, the upper feed wheel, together with a channel 15 knife and a grooving knife, are adapted to move up and down in accordance with variations in the thickness of the work; and the width of the channel is gaged by an edge roll which is mounted in fixed vertical relation to the lower feed roll and is usually 20 geared to the latter so as to be driven thereby at the same peripheral speed to assist in feeding the work. In order that the channel knife may be capable of adjustment into 25 position to cut a channel extending in a widthwise direction to the edge face of a sole, the edge roll must be located so that the cutting edge of the channel knife will slightly overlap the upper end face of the 30 edge roll and therefore the edge roll can project above the lower feed roll no more than permitted by the channel knife when the latter is adjusted vertically for the thinnest sole which the machine is adapted to 35 operate upon. Consequently although the edge roll will be capable of engaging a thin sole throughout substantially the full width of the edge face of the sole it will engage only the lower portion of the edge face of 40 a relatively thick sole. A thick sole therefore may be inadequately supported against the thrust exerted by the operator in holding the sole against the edge roll, with the result that the outer edge of the channel is 45 liable to be uneven and ragged. In some cases, the material of the sole adjacent to the upper portion of the sole edge may be crowded somewhat over the upper surface

of the edge roll, or the margin of the sole may even force its way into the space between the channel knife and the edge roll to such an extent as to interfere with the feed of the sole. 50

One object of the present invention is to overcome the difficulties above mentioned and to this end a feature of the invention consists in the combination, with a work support and a channel knife movable relatively to the work support and in response to variations in the thickness of the work, 55 of a yieldingly supported edge gage, and means movable in unison with the knife for determining the relative positions of the knife and the edge gage. In the illustrated embodiment of the invention, the lower feed roll is mounted upon a stationary frame, the upper feed roll is carried by a head 60 which is pivoted upon the frame for up-and-down adjustment relatively thereto, the edge roll is supported by the stationary frame 65 and driven through connections with the lower feed roll constructed and arranged to permit the edge roll to rise and fall with the head, and yielding means is provided for holding the edge roll continuously in engagement with a portion of the head so that 70 it will partake of the up-and-down movement thereof. Such an organization enables the edge roll and the cutting means relatively to be adjusted in the desired intimate 75 relation necessary to secure clean cutting operations and continuously to be maintained in such relation irrespective of variations in the thickness of the work. As a result, the edge roll will engage the sole 80 throughout substantially the full width of the sole edge even upon the thickest sole. The work will therefore be adequately supported against the edgewise thrust exerted by the operator and a clean cut channel 85 clear to the extreme edge of the sole will be insured whenever desired. 90

In machines of the type above referred to, as heretofore constructed, angular adjustment of the channel knife has been secured 95 by loosening the means which clamps the

knife to the knife block and shifting the knife angularly relatively to the knife block. Such procedure, however, is liable to disturb the vertical or horizontal adjustment of the cutting edge of the channel knife relatively to the cutting edge of the grooving knife so that the groove may not be cut to the desired depth or located accurately with respect to the channel cut. The proper relative horizontal and vertical adjustment of the channel and grooving knives is usually effected only after more or less experimenting and careful manipulation on the part of the operator, and once such an adjustment is properly made, it is desirable that it shall not be disturbed by subsequent changes in the angular adjustment of the channel knife tending to result in variation in the depth or location of the groove.

To avoid the above-mentioned disadvantages resulting from the customary manner of angularly adjusting the channel knife, and to insure that the free extremity of the cutting edge of the channel knife shall be retained in the same relation to the cutting edge of the grooving knife irrespective of variation in the angular adjustment of the channel knife, another feature of the present invention consists in the combination with a grooving knife, of a channel knife guided for angular or tilting adjustment about an axis which may be made coincident with or closely adjacent to the axis of the grooving knife.

Other features of the invention relate to the provision of a reorganized channeling machine of the above-mentioned type embodying certain improvements in the form and arrangement of the knife carriers whereby various adjustments of the channel and grooving knives may conveniently be effected; to the provision of improved means for detachably securing the knife-carrying head to the frame of the machine; to the provision of simple and convenient means for adjusting the knife-carrying head transversely of the direction of work feed which may be set to secure an accurate predetermined adjustment of the width of the channel and which will not interfere with the removal of the head from the machine; and to a machine organization constructed and arranged to facilitate the manual control and adjustment of various operations of the machine.

The invention further consists in features of construction and combinations and arrangements of parts hereinafter described and claimed.

In the accompanying drawings,

Fig. 1 is a side elevational view, partially broken away, of a machine constructed in accordance with the present invention;

Fig. 2 is a detail sectional view of one of the locking pins shown in Fig. 1;

Fig. 3 is a perspective view of a portion of the machine, illustrating particularly the mounting of the knives and knife-carrying devices in the swinging head;

Fig. 4 is a perspective view illustrating particularly the construction of a modified form of knife block adapted to carry two grooving knives;

Fig. 5 is a perspective view of the reversible channel knife;

Fig. 6 is a detail elevational view showing a portion of the channel knife slide and the parts supported thereby;

Fig. 7 is a vertical sectional view, on an enlarged scale, of a portion of the machine, showing particularly the construction of the edge gage and the lower feed wheel and the mounting of the channel knife;

Fig. 8 is a perspective view, partially in section, of the edge gage roll;

Fig. 9 is a perspective view showing the means for adjusting the knife-carrying head transversely in the direction of work feed;

Fig. 10 is a detail sectional view showing the operating instrumentalities and illustrating their operation upon a sole;

Fig. 11 is a perspective view showing the arrangement of the foot treads;

Fig. 12 is a detail view illustrating the mechanism for connecting the machine continuously with power, the view being partially in section on the line 12-12 of Fig. 1;

Fig. 13 is a perspective view, showing parts of the operating instrumentalities of the machine illustrated in the preceding views, and showing also a portion of a sole being operated upon thereby; and

Figs. 14, 15 and 16 are perspective views showing portions of soles which have been operated upon by the present machine and illustrating different ways of grooving the sole.

Referring to the drawings, the instrumentalities which operate upon the work comprise a lower feed wheel 20 (Fig. 1), a rotary edge gage or edge roll 22, an upper feed wheel 24, a presser foot 26, a channel knife 28 and a grooving knife 30 (Fig. 3). The lower feed wheel and the edge roll are mounted upon a lower or main frame 32 (Fig. 1), while the upper feed wheel, the presser foot and the knives are supported by an upper frame or head 34 which is detachably mounted upon the main frame with provision for a limited amount of up-and-down swinging movement relatively thereto and also for horizontal adjustment transversely of the direction of work feed. The main frame 32 is formed with a depending cylindrical post 36 which is received within a hollow pedestal 38 adapted to be bolted to a bench or other support. The upper portion of the pedestal 38 is split vertically and is adapted to be contracted against the post 36 by means of a collar screw 40 so that

the frame 32 may be secured in any desired position of adjustment about the axis of the pedestal.

The lower feed wheel is rigidly secured 8 to the outer end of a horizontal shaft 42 which is journaled in suitable bearings in the main frame. The upper feed wheel 24 is carried at the outer end of a horizontal shaft 44 which is journaled in bearings formed in 10 the head 34 and is adapted to be driven from the lower feed wheel shaft 42 through intermeshing gears 46 and 48 on the shafts 42 and 44 respectively. The gear 46 also meshes with a pinion 50 fast on a main shaft 52 15 which is journaled in bearings in the frame 32 and derives its motion from a pulley 54 which is rotatably and slidably mounted on said shaft and is adapted to be connected by means of a belt 56 with any suitable source 20 of power.

The pulley 54 is adapted to be connected with the main shaft 52 through a friction clutch comprising an annular driving clutch member 58 formed on the outer side of the 25 pulley 54 and having a smooth lateral face arranged to cooperate with a driven clutch member in the form of a friction ring 60 fixedly secured to the inner side of a hand wheel 62 which is keyed to the main shaft 30 and is retained in place by means of lock-nuts 64.

The pulley carrying the driving clutch member 58 is adapted to be shifted bodily toward the hand wheel 62 so as to engage 35 the members of the friction clutch and thereby connect the main shaft with power by means of a wedge block 66 which is slotted to receive the shaft and is connected, through a rod 67, with a foot treadle 68 (Fig. 11) 40 normally held in elevated position by means of a suitably arranged spring 69. The inclined face of the wedge block 66 cooperates with a similar inclined wedge face formed on a collar 70 slidably mounted on the main shaft 45 52 between the wedge block and the pulley, the collar being formed with a depending portion carrying laterally offset lugs 72 which straddle the lower portion of the wedge block to prevent the collar 70 from 50 turning with the shaft and pulley. With the above described construction, as long as the treadle 68 is held depressed, the driving clutch member 58 will be held in contact with the friction ring 60 and the main shaft 55 will be rotated under power, but when the treadle is released the pulley 54 will turn idly upon the driving shaft. Upon release of the foot treadle, the hand wheel 62 may be used as a brake to reduce or arrest the speed 60 of the machine. In practice, it is found convenient for the operator to thus slow up the machine while operating around the toe or other abruptly curved portion of the margin of a sole.

65 Under certain conditions, it is desirable

to have the machine run continuously and in order that this result may be obtained without it being necessary for the operator to hold the treadle 68 depressed, a latch device is provided for holding the wedge block 66 70

in its lowered position. The arrangement is such that normally the latch device is maintained inoperative, but it is capable of being set so that it will become operative, either upon the depression of the foot treadle which 75 actuates the wedge block, or upon the depression of a conveniently located hand lever 74. To this end the hand lever 74 is pivoted at 76 to an adjustable post 78 carried by the pedestal 38 and is connected by means of a 80 spring 80 with a pin 82 projecting from the pedestal 38. The hand lever 74 is longitudinally slotted at 84 and is bored in a direction at right angles to the length of the slot 84 to provide apertures 86 through which the 85 treadle rod 67 extends loosely. A collar 88, rigidly secured to the treadle rod 67, is received within the slot 84, thus connecting the treadle rod with the hand lever 74 so that depression of the latter will operate to throw 90 the clutch. To latch the wedge block 66 in its lower position so as to hold the clutch members engaged, a latch 90 is pivoted at 92 upon the hand lever 74, the latch being notched at its upper extremity to provide 95 shoulders for engaging the pin 82. The latch 90 is yieldingly held in engagement with the pin 82 by means of the spring 94 confined between the hand lever 74 and a thumb piece 96 projecting from the latch 90. 100 Upon depression of the hand lever 74 from the position shown by dotted lines to the position shown in full lines in Fig. 12 the spring 94 functions to throw the latch 70 into cooperative engagement with the pin 105 100 105 110 115 120 125

82, thus latching the lever 74, together with the treadle rod 67 and the wedge block 66, in their lowered positions and holding the clutch members engaged. By depressing the thumb piece 96 the latch 90 may be readily released for the purpose of disengaging the clutch members. In order that the latch 90 shall not function, except when desired, to maintain engagement of the clutch members, a pawl 98 is pivoted at 100 to the hand lever 110 115 120 125 130 135 140 145 150 155 pawl and above the shoulder 102 the pawl 90 is thickened, as indicated at 103, to limit the movement of the pawl. Downward movement of the pawl 98 is limited by the shoulder formed at the lower side of the notch 104.

As shown in Fig. 7, the feed wheel 20 comprises three disks 106 formed with serrated peripheries and arranged side-by-side upon a sleeve 108 keyed to the shaft 42. The feed wheel disks 106 are held in fixed relation to each other on the shaft 42 by means of screws, one of which is shown at 110, the screws extending through a disk-like flange 112 formed integrally with the sleeve 108 and being threaded into a bevel gear 114. The gear 114 is located at the inner side of the flange 112 and transmits rotation to the edge gage 22 as will hereinafter appear. The flange 112 turns with the feed roll 20 and has a smooth periphery adapted to support the extreme edge portion of the sole. A dish-like shield or guard 116 is secured, by means of a screw 118, to the outer end of the shaft 42 to cover the outer face of the feed wheel and protects the hands of the operator from being injured by the heads of the screws 110 or by other engagement with the feed wheel. The periphery of the guard 116, although not overlapping the teeth of the outer feed wheel disk, is located closely adjacent to the base of these teeth and on account of the bulging character of the guard it functions effectively to prevent the operator's fingers from being injured by the feed wheel teeth while guiding a sole through the machine. It will be appreciated that the guard 116 performs its function without in any degree interfering with the feed of the work.

The edge gage 22 is made in the form of a roller and is carried by a bevel pinion 120 which meshes with the bevel gear 114 carried by the lower feed wheel. The bevel pinion 120 is mounted to turn upon a post 122 rising from a slide 124 which is rigidly but adjustably secured within a guideway 126 in the frame 32. The outer end of the slide 124 is rectangular in form, its lower side resting upon a flat supporting face 128 formed upon the main frame 32, while the upper face of the slide 124 affords a flat bearing surface upon which the pinion 120 may freely turn. The slide 124 is adapted to be adjusted longitudinally in its socket, to secure the desired close relation of the edge gage roll to the lower feed roll, by means of a screw 130 threaded in the rear extremity of the slide and passing loosely through the frame at the end of the guideway 126. The screw 130 is formed with a head 132 which bears against the shoulder on the frame 32 and by means of the head the screw may be turned to effect the desired horizontal adjustment of the edge gage roll. A suitable binding or locking device 134 may be employed to re-

tain the slide 124 in adjusted position, and the post 122 may be detachably secured to the slide 124 by means of a similar locking device 136.

It is desirable that the edge roll shall be positively driven and yet shall be capable of moving up and down in accordance with variations in the thickness of the work so that, irrespective of such variations, the edge roll will at all times be located in the same relation to the knives and the presser foot. To this end, as shown clearly in Figs. 7 and 8, the edge roll 22 is supported immediately above the bevel pinion 120 and is guided for up-and-down movement by means of the post 122 and a plurality of studs 142, the post 122 extending through the pinion 120 and being received in a central aperture 140 in the edge gage roll, and the studs 142 being carried by the bevel pinion 120 and projecting upwardly into apertures 144 in the edge roll. The edge roll is yieldingly supported by means of a plurality of coil springs 146 the opposite ends of which are seated in recesses formed in the edge roll and in the pinion 120. As shown the guiding studs 142 are made in the form of screws threaded into the pinion 120 and having enlarged heads 148 which are received in recesses formed in the upper face of the edge roll by counter-boring the apertures 144. The heads of the studs 142 serve as stops to limit the upward movement of the edge roll under the influence of the springs 146.

When the machine is in operation, the edge roll is thrust downwardly against the force of the springs 146 by means of a member carried by the head 134 which engages the flat upper surface of the edge roll, as will hereinafter be described. The mounting of the edge roll is such that while it is constrained to rotate in unison with the pinion 120, it is free to move either up or down in unison with the head 34 as the latter rises or falls with variations in the thickness of the work. In addition, due to looseness in the fitting of the pins 142 and the post 122 in the apertures 144 and 140 respectively the edge roll has a very slight tilting movement of accommodation enabling it to adjust itself to slight changes in angularity of the surface against which it is pressed by the spring 146. As shown, the periphery of the edge roll is cut away at the upper side of the roll, as shown at 150, thus providing ample clearance to allow for adjustment of the channel knife transversely of the lower feed roll and also for angular adjustment of the channel knife. The clearance space afforded by the cutting away of the edge roll enables the heel of the channel knife blade to be set out outwardly beyond the sole edge so that the channel will extend to the extreme edge of the sole.

The right-hand end of the head 34 (as

viewed in Fig. 1) is loosely pivoted to the frame 32 by means of a pin 152 which extends through ears supported by the frame 32 and through an opening in a slot 154 in the head 34. At a point considerably above the level of the slot 154 a second open-ended slot 156 is formed in the head 34 to receive a roller 158 carried at the outer end of a horizontal stud 160. The stud 160 is supported by an arm 162 (Fig. 3) fixedly secured to the upper extremity of a post 164 which is slidable vertically in the frame 32.

In order that the head 34 may be easily and quickly removed from the frame 32, the stud 160 is arranged so that it may be readily withdrawn from the slot 156. To this end, the stud 160 is detachably secured to the block 162 by means of a pin 166 which extends freely through the block 162, transversely of the stud 160, and is formed with a semi-cylindrical notch 168 (Fig. 2) in its side, the notch being adapted to receive the stud 160. The upper end of the locking pin 166 is threaded to receive a wing nut 170 which, when tightened, causes one side of the notch 168 to clamp the stud 166. The stud 160 extends outwardly beyond the block 162 and is knurled at 172 to facilitate its removal.

The use of a locking pin of the character just described is advantageous since it affords a means for securely locking a smoothly finished cylindrical member without possibility of injuring the finished surface thereof. The locking devices, 134 and 136, hereinbefore mentioned, may comprise pins formed with cylindrical notches, such as the notch 168, to receive the slide 124 and the post 122, respectively, and said pins may be provided with suitable nuts arranged to draw the pins into clamping positions.

The post 164, which carries the supporting block 162 and the stud 160, is slidable vertically in bearings 174 on the main frame 45 and a spring 176 encircles the post 164, between the upper bearings 174 and a collar 178 threaded upon the post, the force of the spring acting through the block 162 and the roller 158 to force the unpivoted end of the head 34 downwardly to hold the knives in the work. In order to move the operating instrumentalities carried by the head 34 away from the lower feed roll to facilitate the introduction and removal of the work, the head 34 is adapted to be raised against the action of the spring 176 by means of a foot treadle 180 (Fig. 11) and a treadle rod 182 (see also Fig. 1) the rod 182 being alined with the post 164 and abutting the lower end 55 thereof. The treadle 180 is pivoted at 184 to a floor bracket 186 and a spring 188 is arranged to return the treadle to raised or inactive position.

The downward swinging movement of the head 34 is limited by means of a stop screw

190 threaded at 192 into the upper bearing 174. The stop screw 190 is formed with an enlarged central portion 194 which is received in the counterbored lower portion of an aperture 196 in the supporting block 162. 70 The reduced upper portion of the stop screw 190 extends freely through the aperture 196, and above the block 162 the stop screw is provided with a square head adapted to receive a wrench by means of which it may be turned to vary the elevation of the stop shoulder 194 and thus to vary the vertical adjustment of the head 34. Below the threaded portion of the stop screw 190 a reduced extension 198 projects beyond the lower side of the bearing 174 and a lock-nut 200 on said extension is arranged to secure the stop screw 190 in adjusted position. An auxiliary stop screw 202, carried by the frame 32, insures against the possibility of the knives coming in contact with the toothed lower feed wheel 20 on account of improper adjustment of the stop screw 190. The head 34 is guided in its vertical swinging movement between spaced wings one of which is shown at 204, these wings rising from the frame 32 and engaging finished bearing surfaces at opposite sides of the head. The gears 46 and 48 being located closely adjacent to the pivot pin 152 will not become disengaged from one another by the upward swinging movement of the head. The holdown effect of the spring 176 is particularly effective inasmuch as the force of the spring is applied through the roller 158 at a point remote from the pivot pin 152 and near the operating instrumentalities. 95

The above described horizontal slots 154 and 156 permit adjustment of the head transversely of the direction of work feed so as to position the knives relatively to the sole edge so that a wide or narrow shoulder may be formed between the channel and the edge of the sole, or, if desired, the channel may be made to extend to the edge face of the sole, either at the upper corner thereof, or to a line below said corner. To effect such transverse adjustment of the head 34, an adjusting sleeve 206 (Fig. 9) is employed, the sleeve having an eccentric 208 formed thereon for engagement with the opposite curved sides of a slot 210 in the head. As shown, the adjusting sleeve 206 is mounted to turn on a fixed stud 212 projecting from the frame 32 and a knurled head 214 is provided for turning the sleeve. The opposite curved sides of the slot 210 are struck from a center in the axis of the pivot stud 152 and the slot is open at its lower end to enable the head 34 to be readily detached from the frame 32. A lock-nut 216 on the stud 212 is adapted to bind the sleeve 206 against the frame 32 to secure the sleeve and the head 34 in adjusted position. As shown in Fig. 9, suitable graduations may be provided upon 120 125 130

the head 214, and a suitable cooperating mark upon an adjacent portion of the frame 32 to assist in the transverse adjustment of the head.

5 The upper feed roll 24 is keyed to the outer extremity of the shaft 44 and is retained against axial movement between the end face by a bearing 218 on the head and a collar 220 secured by means of a screw to 10 the end of the shaft 44. The presser foot 26 is fixedly secured by means of a screw 222 to the side of the bearing 218, the screw 222 extending through a longitudinal slot 224 in the shank of the presser foot to permit vertical 15 adjustment of the presser foot. As shown, the upper feed wheel 24 and the presser foot 26 are located side-by-side above the lower feed wheel 20 and said feed wheels cooperate in the usual manner to feed the 20 work, while the presser foot performs its usual function of gaging the depth of the cuts made by the knives. In addition, the presser foot assists the upper feed roll to hold the work against the lower feed roll. 25 It will be seen that the upper feed wheel is offset outwardly relatively to the lower feed wheel and that the lowermost point in the periphery of the upper feed wheel lies substantially in the horizontal plane of the 30 pivoted axis of the head. In order to insure contact of the upper feed wheel roll with the work throughout the entire width of the roll, irrespective of the angular adjustment of the head 34 about its pivotal axis, the 35 periphery of the roll 24 is slightly tapered axially, the diameter of the outer edge of its periphery being greater than the diameter of the inner edge thereof, so that when the head is swung upwardly to accommodate a thicker portion in the work, the outer edge 40 of the feed roll will not be lifted out of feeding engagement with the work.

The channel knife 28 is formed with a rectangular shank 228 and with a laterally offset blade provided with a cutting edge at each end of the shank. The channel knife is made with two cutting edges so that when one edge has become dull a sharp cutting edge will be immediately available and may be quickly placed in position by reversing the knife end-for-end relatively to the block to which the knife is removably secured. The two blades are laterally offset in opposite directions so that when the knife is secured in place one blade will project downwardly and the other blade will project upwardly with respect to the shank of the knife. This construction insures that the inactive or reserve blade will be located out of the way where it will not be liable to be damaged or to interfere with the action of any of the operating parts of the machine. As shown in Fig. 5, the heel or rear portion of each blade of the channel knife is notched 60 at 229 to enable the cutting edge of the 65

grooving knife to be adjusted in the desired close relation to the cutting edge of the channel knife.

The channel knife 28 is carried by a knife block or holder 230 having surfaces 232 and 234 arranged at right angles to each other to form a seat for the rectangular shank portion of the knife, and the shank of the knife is adjustably held to its seat by means of a clamp plate 236, which is tightened against 70 the knife by a collar screw 237, said screw extending through the knife block 230 and being threaded into the clamp plate. Co-operating bevel faces 232 and 234 on the clamp plate 236 and the knife block 230 hold 80 the shank of the knife seated against the faces 232 and 234 on the knife block. The knife block 230 has a horizontal tongue-and-groove connection 238 with a knife block holder 240 which permits adjustments of the 85 knife relatively to the presser foot and feed wheels in the direction of feed. The knife block is adapted to be clamped in adjusted position upon the knife block holder 240 by means of a collar screw 242 which extends through a slot 244 in the knife block and is threaded into the knife block holder. 90

To facilitate angular adjustment of the channel knife, the knife block holder 240 is formed with a segmental face 241 arranged for sliding adjustment along a corresponding segmental face on the lower portion of a vertical slide or carrier 245, an arcuate tongue-and-groove connection 243 being provided between the holder 240 and the slide. 100 The cooperating segmental faces and tongue-and-groove connections between the knife block holder and the knife slide are curved about a center so arranged that the point of the channel knife, or the point of the 105 grooving knife, or the points of both said knives may be made to coincide substantially therewith as may be desired. The lower portion of the slide 245 is split lengthwise of the tongue-and-groove connections 243, as shown at 246, and the split portions of the slide are adapted to be contracted by means of a collar screw 248 to secure the knife block holder 240 in its angularly adjusted position. As shown in 110 Fig. 1, a suitable mark upon the side of the knife block holder 240 may be arranged to cooperate with the graduations of a scale 249 on the lower portion of the channel knife slide 245 to enable the channel knife to be set to cut a channel at a predetermined angle 115 with respect to the face of the sole. By providing the above described segmental tongue-and-groove mounting for the channel knife block holder, any desired angular or tilting 120 adjustment of the channel knife may be conveniently obtained and the angular adjustment of the channel knife may be changed at will without disturbing the adjustment of the channel knife relatively to the knife 125 130

block. Also if the grooving knife is arranged with its cutting point substantially in line with the axis of tilting adjustment of the channel knife, variation in the angular adjustment of the channel knife will not result in change in the depth of the groove or change in the location of the groove relatively to the cut portion of the channel.

The channel knife slide or carrier 245 is mounted in a guideway 250 formed in the head 32, the outer side of the guideway being formed by a removable plate 252. The slide 245 is supported in the guideway 250 by means of a rod 254 pinned at its lower extremity to the slide and passing through an apertured ear 256 on the head, the upper end of the rod 254 being threaded to receive an adjusting nut 258 which bears against the upper side of the ear 256 and constitutes a stop to limit the downward movement of the channel knife slide as well as a means for adjusting the channel knife vertically relatively to the grooving knife and the upper feed wheel. The channel knife slide is pressed downwardly by means of a spring 260 which encircles the rod 254 between the upper end of the slide and the ear 256. A lock-nut 262 is arranged to prevent accidental displacement of the adjusting nut 258. As shown in Figs. 6 and 7, the channel knife block 230 is formed with a flat lower face 263 of an area sufficiently large to cover substantially the entire upper surface of the edge roll 22. With this construction it has been found that there is no tendency for the edge roll to cramp or bind upon the pins 142 or the post 122 as a result of the very slight tilting movement of the head in response to variations in the thickness of the work.

The grooving knife 30 is of the usual tubular construction and is carried at one end on a rectangular shank 264 which is adjustably held by a clamp plate 265 and a collar screw 266 against perpendicularly disposed locating shoulders formed in a knife block 268. The knife block 268 is formed with a laterally offset lug 267 having a horizontal tongue-and-groove connection 269 with a knife block holder 270 to which it is clamped by a collar screw 272, said screw extending through a slot 274 in the knife block and being threaded into the knife block holder. The tongue-and-groove connection 269 permits adjustment of the grooving knife relatively to the channel knife in the direction of feed. This adjustment may conveniently be made by means of a wrench inserted through one of the perforations 275 in the upper feed wheel. The knife block holder 270 has a horizontal tongue-and-groove connection 276 with a vertically movable slide or carrier 277, and a collar screw 278 which extends through a slot 280 in the knife block holder 270, is threaded into the slide 277 to secure the holder in adjusted position relatively to the slide. As shown, the tongue-and-groove connection 276 extends longitudinally at right angles to the connection 269 between the knife block and the knife block holder, thus permitting adjustment of the 70 grooving knife either with or relatively to the channel knife in a direction transversely of the direction of work feed. By means of this arrangement the depth of the channel and the distance between the groove and the edge of the sole may be adjusted independently of each other to vary the relation between these dimensions, or either may be adjusted to compensate for a change in the adjustment of the other so as to maintain a 80 constant relation between the depth of the channel and the distance between the groove and the sole edge.

The grooving knife slide 277 is held by a removable plate 282 in a guideway 284 in the head 34 and the slide pressed downwardly by a spring 286 located between the slide and a lug 288 on the head. The spring 286 encircles an adjusting screw 290 having a knurled head 292 and a shank the lower portion of which is threaded into the knife slide 277 while the upper portion of the screw shank extends freely through the lug 288. A stop collar 294 on the shank of the adjusting screw 290 is received in a recess 296 in the lug 288, the recess being shaped to permit upward movement of the slide 277 relatively to the head under the influence of the spring 286, so that the grooving knife may be lifted out of the work independently of the channel knife for reasons well known in the art. The shoulder formed at the lower extremity of the recess 296 limits the downward movement of the grooving knife slide, while the shoulder formed at the upper extremity of said recess limits the upward movement of the slide. By turning the screw 290 by means of the knurled head 292, the normal vertical position of the slide 277 relatively to the head 34 may be adjusted 100 to vary the depth of the groove in the work. In order that the screw 290 may be prevented from turning after it has been adjusted, a tail 298 at the lower end of the screw extends through a semi-circular notch 300 in a locking pin 302 which extends freely through the slide 277 at right angles to the screw 290 and through a vertical slot 304 in the plate 282. A wing nut 306 threaded on the outer end of the pin 302 may be turned to draw the pin outwardly so that the tail of the screw 290 will be tightly clamped by one side of the notch 300. The vertical slot 304 permits upward movement of the slide 277.

It is sometimes desirable to cut a channel along certain parts of the sole margin, e. g., around the toe, without also cutting the groove in the channel. To enable this result to be accomplished provision is made for 120 125 130

lifting the grooving knife independently of the channel knife. To this end, a lever 310 is pivoted at 312 to the head 34 and the short arm of the lever engages beneath the knurled head of the screw 290. The long arm of the lever 310 is detachably connected at a point near the pivotal axis of the head 34 with a treadle rod 314 which, in turn, is connected with a foot treadle 316 (Fig. 11). 5 The treadle 316 is adapted to be depressed to raise the grooving knife slide 277 so as to lift the grooving knife out of the work. A spring 318 is arranged to return the foot treadle 316 to inactive position. Fig. 13 10 shows a portion of the toe of a sole which has been prepared by a machine embodying the present invention and in which both the channel 320 and the groove 322 are continuous around the toe. Fig. 14 illustrates the 15 result of raising the grooving knife independently of the channel knife by means of the treadle 316, the groove 322 in this figure being omitted around the toe.

It is sometimes desirable to cut parallel 20 grooves instead of a single groove in the channeled portion of the sole and for this purpose, an additional grooving knife 324 (Fig. 4) may be employed. As shown, this grooving knife 324 is formed with a shank 25 portion 326 and the grooving knife block 268 may be formed with an extension 328 grooved as shown at 330 to receive the shank 326 of the additional grooving knife 324. The grooving knife 324 is secured in place 30 on the extension 328 of the grooving knife block by means of a clamp plate 332 and a collar screw 334 which extends through the clamp plate and is threaded into the extension of the knife block. The collar screw 35 334 may be loosened to enable the grooving knife to be adjusted vertically relatively to the grooving knife 30. By loosening the screw 266, a relative adjustment of the grooving knives 30 and 324 toward or from 40 each other transversely of the direction of work feed may be readily effected. Fig. 15 shows a portion of a channeled sole in which parallel grooves 336 have been cut by means of the knives 30 and 324, and Fig. 16 is a 45 similar view showing a portion of a sole in which parallel grooves terminate short of the toe end of the sole.

It will be seen from the foregoing description that the illustrated machine embodies 50 various improvements in the form and arrangement of the devices for supporting the channel and grooving knives whereby these knives may be adjusted each independently of the other horizontally, both in the direction of work feed and transversely thereof, as well as vertically relatively to the swinging head 34. The presser foot 36 is also 55 adjustable vertically with respect to the head and the knives. The channel knife, in addition to being adjustable both vertically

and horizontally as described, is capable of being adjusted angularly in a vertical plane transverse to the direction of work feed without disturbing the vertical and horizontal adjustment of the knife relatively to the other operative parts of the machine. Thus it is unnecessary for the operator carefully to readjust the channel knife horizontally and vertically after a suitable angular adjustment has been secured and consequently 70 a considerable saving of time is effected whenever the angular adjustment of the knife is changed. The construction of the parts supporting the channel knife is such that a suitable scale may be employed, as 75 described, for determining the angular adjustment of the channel knife in accordance with the angle at which it is desired to cut the channel. The channel and grooving knives are adjustable in unison transversely 80 of the direction of work feed and relatively to the edge roll to vary the distance between the channel and the edge of the sole. The eccentric adjusting sleeve 206, which is 85 turned by means of the knurled head 214 conveniently located at the side of the machine, provides for a very fine and accurate adjustment of the knife-carrying head 34 transversely of the direction of work feed. The eccentric sleeve 206 may conveniently 90 be locked against turning to secure the head 34 in adjusted position. The scale upon the periphery of the knurled head 214 enables the channel knife to be adjusted so 95 that a shoulder of a desired width may be obtained between the channel and the sole edge and the construction is such that the setting of the eccentric sleeve is not disturbed by the removal of the head from the machine. The head 34 may be quickly and 100 easily removed from the frame 32 to afford access to various parts of the mechanism for the purpose of making repairs and various adjustments, such, for example, as the reversal of the channel knife. To remove the 105 head 34, it is necessary only to loosen the wing nut 170 and withdraw the stud 160 from the slot 156. Thereafter the head may be disengaged from the frame 32 by an upward movement without it being necessary 110 to manipulate any of the connections between the head and the frame.

The invention having been described, what I claim as new and desire to secure by Letters Patent of the United States is:—

120

1. In a machine of the class described, means for supporting and feeding the work, cutting means movable toward and from the work-supporting means in response to variations in the thickness of the work, a holder for the cutting means, and an edge gage yieldingly held in engagement with said holder for movement in unison with said movement of the cutting means.

125

2. In a machine of the class described, 130

means for supporting and feeding the work, cutting means movable vertically in response to variations in the thickness of the work, an edge gage mounted for vertical adjustment, and yielding means for adjusting the edge gage vertically in unison with the cutting means.

3. In a machine of the class described, the combination with a work support and a channel knife movable relatively to the work support and in response to variations in the thickness of the work, of a yieldingly supported edge gage, and means movable in unison with the knife for determining the relative positions of the knife and the edge gage.

4. In a machine of the class described, the combination with a work support and a channel knife movable relatively to the work support and in accordance with variations in the thickness of the work, of an edge gage roll movable in unison with the channel knife, and means for driving the edge gage roll.

5. In a machine of the class described, in combination, a feed wheel arranged to support the work, a channel knife movable toward and from the feed wheel, and an edge gage roll driven from the feed wheel and movable in unison with the channel knife.

6. In a machine of the class described, a stationary frame, a rotary work support carried thereby, a head mounted on the frame and movable up and down relatively to the work support, a channel knife carried by the head, and an edge gage carried by the frame and arranged to partake of the up and down movement of the head.

7. In a machine of the class described, a stationary frame, a rotary work support carried thereby, a head mounted on the frame and movable up and down relatively to the work support, a channel knife carried by the head, an edge gage carried by said frame, and means for yieldingly pressing the edge gage upwardly against said head so that the edge gage will be maintained in predetermined relation to the head as the latter moves up or down.

8. In a machine of the class described, a stationary frame, a feed wheel carried by the frame and arranged to support the work, a driven member mounted on the frame and rotatable about an axis at right angles to the axis of the feed wheel, a head movable up and down relatively to the frame, a channel knife carried by the head, and an edge gage roll carried by said member and rotatable in unison therewith while being movable up and down in unison with the head.

9. In a machine of the class described, a stationary frame, a work supporting feed wheel, a driven member mounted on the

frame and rotatable about an axis at right angles to the axis of the feed wheel, an edge gage roll coaxial with said driven member, vertically slidably driving connections between said member and the edge gage roll, and means for yieldingly maintaining the edge gage roll in contact with the head.

10. In a machine of the class described, a stationary frame carrying a work support, a head pivotally mounted on the frame, a channel knife carried by the head, a driven member supported by the frame and rotatable about a vertical axis, and a floating edge gage roll rotatable in unison with said member and constructed and arranged to move up and down and to tilt in unison with the head.

11. In a machine of the class described, a stationary frame, a driven feed wheel carried by the frame, an edge gage roll rotatable about a vertical axis, intermeshing bevel gears connecting the edge gage roll with the feed wheel, driving connections between the driven gear and the edge gage roll arranged to permit up and down and tilting movement of the roll, springs urging the edge gage roll upwardly, means for limiting the upward movement of the roll, a head movable up and down relatively to the frame and carrying a channel knife, and means on the head for engaging the edge gage roll to keep it normally in fixed vertical relation to the knife.

12. In a machine of the class described, a stationary frame, a driven feed wheel carried thereby, an edge gage roll having apertures therein, a driven rotary member coaxial with the edge gage roll, pins carried by said member and extending into said apertures, springs between said roll and said member urging the roll upwardly, heads on the pins above said apertures to limit the upward movement of the roll, and a head movable up and down relatively to the frame and carrying a channel knife, and normally engaging said roll to maintain the latter in a predetermined relation to the knife.

13. In a machine of the class described, the combination with a feed wheel arranged to support the work, of a channel knife movable toward and from the feed wheel, of an edge gage roll driven from the feed wheel and adjustable both axially of the feed wheel and radially thereof.

14. In a machine of the class described, a stationary frame, a head movable up and down relatively to the frame, a driven feed wheel and an edge gage roll on the frame, a channel knife and a presser foot on the head, and driving connections between the feed wheel and the edge gage roll constructed and arranged to enable the edge gage roll to move up and down in unison with the head.

15. In a machine of the class described, a stationary frame, a head movable up and down relatively to the frame, a driven feed wheel and an edge gage roll on the frame, a channel knife and a presser foot on the head, driving connections between the feed wheel and the edge gage roll constructed and arranged to enable the edge gage roll to maintain a predetermined angular relation to the head, and means for adjusting the edge gage roll axially of the feed roll.
16. In a machine of the class described, in combination a frame, a work supporting feed roll mounted on the frame, a head movable up and down relatively to the feed roll, an adjustable channel knife carried by the head, and an edge gage roll mounted on the frame and yieldingly pressed upwardly to maintain its upper face in engagement with a portion of the head, said roll having a portion of its upper face cut away to permit adjustment of the channel knife.
17. In a machine of the class described, a grooving knife and a channel knife guided for angular adjusting about the axis of the grooving knife.
18. In a machine of the class described, a grooving knife, a channel knife, and a carrier for the channel knife mounted for angular adjustment about the axis of the grooving knife.
19. In a machine of the class described, a grooving knife, a channel knife, a carrier for the channel knife, and a support for the carrier, the carrier having a segmental tongue-and-groove connection with the support constructed and arranged to render the channel knife angularly adjustable about the axis of the grooving knife.
20. In a machine of the class described, a channel knife, a grooving knife, a carrier and a block having slidable adjustable connections with the carrier, means for securing the channel knife to the block and the block to the carrier, a vertically movable slide for supporting the carrier, means for guiding the carrier to tilt the channel knife about the axis of the grooving knife, and means for clamping the carrier to the slide.
21. In a machine of the class described, a reversible channel knife comprising a rectangular shank having a cutting edge at each end extending lengthwise of the shank, the cutting edges being offset laterally from the shank in opposite directions, and a carrier constructed and arranged to support the knife with either cutting edge located in position to operate upon the work and with the other cutting edge removed from the plane of the work.
22. In a machine of the class described, a work support, a reversible channel knife comprising a shank having a blade laterally offset in opposite directions at opposite ends of the shank, and a carrier constructed and arranged to support the knife with one of the blades operatively positioned relatively to the work support.
23. For use in a machine of the class described, a reversible channel knife having a shank formed with parallel faces to be selectively positioned in engagement with a locating face in a knife carrier, a cutting edge at one end of the shank adjacent to one of said parallel faces and a similar cutting edge at the opposite end of the shank adjacent to the other of said parallel faces.
24. For use in a machine of the class described, a channel knife comprising an elongated rectangular shank having cutting edges offset laterally from the shank at each end thereof, said edges being relatively arranged to be selectively located in operative position by reversal end for end of the position of the knife shank in the machine.
25. In a machine of the class described, a driven shaft, a toothed lower feed wheel carried at one end of the shaft, and a guard for the feed wheel comprising a dished plate arranged with its hollow side opposite the outer face of the feed wheel and with its periphery closely adjacent to the inner extremities of the teeth of the feed wheel.
26. In a machine of the class described, a driven shaft, a toothed feed wheel fast upon said shaft and a guard for the feed wheel comprising a dished plate arranged with its hollow side opposite the outer face of the feed wheel and its periphery closely adjacent to the inner extremities of the teeth of the feed wheel, the guard being rigidly secured to the feed wheel so as to rotate in unison therewith.
27. In a machine of the class described, a stationary frame, a lower feed wheel mounted thereon, a head pivoted upon the frame for up-and-down movement, and an upper feed wheel carried by the head and arranged with the lowermost point in its periphery substantially in the horizontal plane of the pivotal axis of the head, the outer edge of said periphery being of greater diameter than the inner edge thereof and being offset outwardly relatively to the lower feed wheel.
28. In a machine of the class described, a frame provided with rotary work-supporting and feeding means, a knife-carrying head pivoted upon the frame with provision for adjustment of the head relatively to the frame transversely of the line of work feed, an eccentric adjusting device for effecting such adjustment of the head, a feed roll mounted upon said head, and means for rotating said work supporting and feeding means and said feed roll.
29. In a machine of the class described, a frame provided with work-supporting and feeding means, a knife-carrying head pivoted upon the frame with provision for adjustment of the head relatively to the frame

transversely of the line of work feed and having a slot therein formed with its opposite sides concentric with the pivotal axis of its head, an eccentric mounted upon the frame and projecting into said slot, and means for turning the eccentric to adjust the frame transversely of the line of work feed.

30. In a machine of the class described, a frame provided with work-supporting and feeding means, a knife-carrying head pivoted upon the frame with provision for adjustment of the head relatively to the frame transversely of the line of work feed and having a slot therein formed with its opposite sides concentric with the pivotal axis of the head, a stud carried by the frame and projecting through said slot, a sleeve mounted to turn on said stud, an eccentric on the sleeve for cooperating with the sides of said slot to adjust the head transversely of the line of work feed, and a head on the sleeve for turning the sleeve.

31. In a machine of the class described, a frame provided with work-supporting and feeding means, a knife-carrying head pivoted upon the frame with provision for adjustment of the head relatively to the frame transversely of the line of work feed and having a slot therein formed with its opposite sides concentric with the pivotal axis of the head, a stud carried by the frame and projecting through said slot, a sleeve mounted to turn on said stud, an eccentric on the sleeve for cooperating with the sides of said slot to adjust the head transversely of the line of work feed, and a lock nut on the stud for binding the sleeve between the nut and the frame to secure the eccentric in adjusted position.

32. In a machine of the class described, a frame provided with work-supporting and feeding means, a knife-carrying head having a pivotal pin-and-slot connection with the head arranged to permit adjustment of the head relatively to the frame transversely of the line of work feed, a second slot being formed in the head having arcuate sides concentric with the axis of said pivot pin, and a rotatable eccentric carried by the frame and projecting into said arcuate slot for adjusting the head transversely of the line of work feed, both of said slots being open at one end to permit the head to be quickly detached from the frame.

33. In a machine of the class described, a frame carrying work-supporting and feeding means, a knife-carrying head pivoted at one end to the frame and having a slot located forward of the pivotal point, a vertically movable slide between said slot and said pivotal point, an arm extending forwardly from said slide, a pin carried by the arm and projecting into said slot and operating with the pivot pin to support the

head, a spring pressing the slide downwardly, a stop to limit the downward movement of the slide, and a treadle rod directly engaging the slide for lifting the head.

34. In a machine of the class described, a frame provided with work-supporting and feeding means, a head pivoted to the frame and capable of being detached therefrom without withdrawing the pivot pin, cutting means carried by the head, a vertically slideable member carried by the frame, detachable interengaging devices carried by the head and said member cooperating to support the head and a spring located between said detachable devices and the pivotal connection between the head and the frame.

35. In a machine of the class described, a frame carrying work-supporting and feeding means, a head pivoted to said frame and having an aperture therein, cutting means carried by the head, a vertically slideable member carried by the frame between said aperture and the pivotal axis of the head, and a stud detachably carried by said member and projecting into the aperture in the head for supporting the head.

36. In a machine of the class described, a frame carrying work-supporting and feeding means, a head pivoted to said frame and having an aperture forward of the pivot point, cutting means carried by the head, a vertically slideable member carried by the frame between said aperture and said pivot point, means detachably carried by said member and projecting into the aperture in the head for supporting the head, and means arranged for pressing said member downwardly to hold the cutting means yieldingly in engagement with the work.

37. In a machine of the class described, a frame carrying work-supporting and feeding means, a head pivoted to said frame and having an aperture therein, cutting means carried by the head, a vertically slideable member carried by the frame, a stud carried by said member and projecting into the aperture in the head, the stud being slidably detachable from said member for supporting the head, means for pressing said member downwardly, and means for limiting the downward movement of said member.

38. In a machine of the class described, a frame carrying work-supporting and feeding means, a head pivoted to the frame and having an aperture forward of the pivot point, cutting means carried by the head, a vertically slideable member carried by the frame between said aperture and said pivot point, a stud detachably secured to said member, and a roller carried by the stud and located in said aperture for supporting the head.

39. In a machine of the class described, a frame carrying work-supporting and feeding means, a head pivoted to the frame and

having an aperture therein, cutting means carried by the head, a vertically slidable member carried by the frame, a stud detachably secured to said member and having a portion projecting from one side of said member for entering said aperture to support the head, and a portion projecting from the opposite side of said member formed for use as a handle in withdrawing the stud from said aperture.

40. In a machine of the class described, a frame carrying work-supporting and feeding means, a head pivoted to the frame, cutting means carried by the head, a vertically slidable member carried by the frame, a stud carried by said member and engaging a portion of the head to support the head, a pin carried by said member and extending transversely of the stud, said pin having a lateral recess through which the stud extends, and releasable means for moving the pin lengthwise to clamp the stud to said member.

41. In a machine of the class described, a frame carrying work-supporting and feeding means, a head pivoted to the frame provided with cutting means, a rod slidable vertically in the frame, a spring urging the rod downwardly, a block fixed to the rod, interengageable devices on said head and block cooperating to support the head, and means for limiting the downward movement of the block, said means being constructed and arranged to prevent said rod from turning.

42. In a machine of the class described, a stationary frame provided with work-supporting and feeding means, a head pivoted upon the frame for up-and-down adjustment and provided with cutting means, a vertically movable slide, an arm extending forwardly from the slide for supporting the head, a spring arranged between the pivotal axis of the head and the cutting means tending to force the arm downwardly, a connection between the forward end of the arm and the head and means for raising the slide against the force of the spring.

43. In a machine of the class described, the combination with channeling and work feeding devices, of a shaft operatively connected with the feeding devices, a driving clutch member rotatably and slidably mounted on said shaft, a driven clutch member fixed to said shaft, operator controlled means for sliding the driving clutch member into cooperative engagement with the driven clutch member, and a latching device operating automatically to hold the clutch members engaged.

44. In a machine of the class described, the combination with channeling and work feeding devices, of a shaft operatively connected with the feeding devices, a driving clutch member rotatably and slidably mounted on said shaft, a driven clutch mem-

ber fixed to said shaft, means for sliding the driving clutch member into cooperative engagement with the driven clutch member, a latching device normally rendered operative by movement of said means for holding the clutch members engaged, and a pawl capable of being set to hold the latching device inoperative.

45. In a machine of the class described, the combination with channeling and work feeding devices, of a shaft operatively connected with the feeding devices, a driving clutch member rotatably and slidably mounted on said shaft, a driven clutch member fixed to said shaft, a cam for sliding the driving clutch member into engagement with the driven clutch member, a hand lever for operating the cam, a manually releasable latch carried on said lever normally operative to lock the cam in active position, and means for rendering the latch inoperative.

46. In a machine of the class described, the combination with channeling and work feed devices, of a shaft operatively connected with the work feeding devices, driving and driven clutch members on said shaft, means including a treadle rod for engaging said clutch members, a hand lever connected to actuate the treadle rod, a latch carried by the hand lever for maintaining the clutch members engaged, and means for rendering said latch inoperative.

47. In a machine of the class described, means for supporting and feeding the work, a knife-carrying head, a carrier movably mounted on the head, a spring urging the carrier downwardly, a knife block holder mounted on the carrier with provision for angular adjustment, a knife block secured to the holder and adjustable in the direction of feed, and a channel knife secured to said block and adjustable transversely of the direction of feed.

48. In a machine of the class described, means for supporting and feeding the work, a knife-carrying head, a carrier mounted for up-and-down adjustment in the head, a knife block holder mounted on the carrier for adjustment transversely of the direction of feed, a knife block carried by said holder and adjustable in the direction of feed, and a grooving knife carried by the knife block.

49. In a machine of the class described, means for supporting and feeding the work, a knife block adjustable in the direction of work feed, a grooving knife mounted for up-and-down adjustment upon the knife block, and a second grooving knife mounted upon the knife block beside the first knife with provision for adjustment toward and from the latter to vary the distance between the grooves cut by the knives.

50. In a machine of the class described, a frame, a head pivoted to the frame for up-and-down adjustment relatively thereto, co-

operating means on the frame and head for feeding the work, and channeling and grooving knives carried by the head, said knives being independently adjustable toward and from the work, and also in the plane of the work, transversely of the direction of feed and said grooving knife being also adjust-

able in the plane of the work in the direction of feed.

In testimony whereof, I have signed my ¹⁰ name of this specification.

ANNE WEBSTER MEYER,
Administratrix of the Estate of William C.
Meyer, Deceased.

CERTIFICATE OF CORRECTION.

Patent No. 1,668,081.

Granted May 1, 1928, to

ANNE WEBSTER MEYER.

It is hereby certified that error appears in the printed specification of the above numbered patent requiring correction as follows: Page 4, line 117, for the word "spring" read "springs"; page 6, line 30, for the word "pivoted" read "pivot-al", and line 85, for the word "adjustments" read "adjustment"; page 10, line 25, claim 17, for the word "adjusting" read "adjustment"; page 11, line 4, claim 29, for "its" read "the"; same page, lines 112 and 113, claim 37, strike out the comma and words ", the stud being slidably detachable from said member" and line 114, after the word "head", insert the words and comma "the stud being slidably detachable from said member,"; page 12, line 46, claim 42, after the word "head" insert a comma, and line 89, claim 46, for the word "feed" read "feeding"; page 13, line 6, claim 50, after the word "work" strike out the comma; and that the said Letters Patent should be read with these corrections therein that the same may conform to the record of the case in the Patent Office.

Signed and sealed this 16th day of April, A. D. 1929.

(Seal)

M. J. Moore,
Acting Commissioner of Patents.
